UNITED STATES PATENT OFFICE.

JOHN J. WOMPEY, OF DENVER, COLORADO.

ATTACHMENT FOR JARS.

1,178,982.

Specification of Letters Patent. Patented Apr. 11, 1916.

Application filed January 8, 1915. Serial No. 1,104.

To all whom it may concern:

Be it known that I, JOHN J. WOMPEY, a citizen of the United States, residing at Denver, in the county of Denver and State of Colorado, have invented certain new and useful Improvements in Attachments for Jars, of which the following is a specification.

This invention relates to attachments for jars, and its object resides in the provision of a device of simple construction which may be readily secured at the mouth of a jar to provide means for the attachment of a cover or other article.

15 The device also serves to protect the neck of the jar against breakage, and its peculiar construction permits of its being applied to jars, the necks of which are of irregular or non-cylindrical form and of varying dimensions.

20 While my invention may be applied to jars or other wide mouthed vessels of any character, it is particularly adapted for use on fruit and preserving jars and more especially on the syrup containers used in soda fountains.

25 When my attachment is employed on jars of the type last-mentioned, it provides a convenient medium for supporting and securing the pump which is usually used in connection with the jars for raising the liquid contained therein.

30 In the accompanying drawings in the various views of which like parts are similarly designated, Figure 1 is a sectional view of the upper portion of a syrup jar, showing my attachment in its operative position, together with the upper part of a pump secured thereto, Fig. 2, a composite 35 elevation and transverse section along the line 2—2, Fig. 1, Fig. 3, a sectional elevation of the upper portion of a jar before the attachment is applied thereto, Figs. 4 and 5, sectional elevations of the coöperative members of the attachment, Fig. 6, a plan view 40 of the member shown in Fig. 5, Fig. 7, a section of the upper portion of a jar and the attachment secured thereto, illustrating a modified method of applying a cover to the latter, and Fig. 8, a similar view showing another modification of the cover.

Referring first to Fig. 6 of the drawings, the numeral 2 designates a jar the mouth of which is surrounded by a short cylindrical neck 3. In the majority of jars of the 55 type used on soda fountains, this neck has an indentation as shown at 4 in Fig. 3, which I employ for more firmly securing the attachment in place, as will hereinafter be described. In this connection I wish it understood, however, that the indentation is not essential for the purpose mentioned and that my attachment may be applied equally well to jars the necks of which are not indented.

60 My attachment consists of two coöperative annular members 5 and 6 one of which is of channel section to be placed over and around the neck of a jar and the other one of which is of angle section to provide substantially 65 rectangularly disposed flanges 7 and 8 which in practice engage respectively the interior shoulder 19 of a vessel around its neck and the inner flange of the outer member around which it is slidingly fitted. In producing the member 6, opposite segments of 70 its outwardly extending flange 7 are omitted as shown in Fig. 6, to reduce its diameter for the purpose of permitting its passage through the mouth of the jar. The other 75 member 5 is provided with suitable means for fastening the pump, cover or other article, to be applied to the jar.

75 In the form illustrated in Figs. 1 and 2, the fastening means above referred to consists of a pair of oppositely disposed headed buttons 9 which serve to secure a flange cover 10 upon the upper surfaces of the outer member 5 of the attachment. The cover is to this end provided with a pair of elongate 80 openings 12 which are formed for the passage of the heads of the buttons at one of their ends, and to receive the shanks of the same at their opposite ends. The cover 10 constitutes the base of a syrup pump 13 85 which is suspended in the jar.

90 To apply the attachment to the jar, its exterior or female member is positioned over the neck of the vessel and its interior or male member is inserted through the mouth of 95 the same and then turned until its flange 8 fits around the inner flange of the outer

member. The two members are then pressed together until the outwardly extending flange of the member 6 firmly engages the shoulder 19 of the vessel around its mouth 5 after which the parts may be permanently secured in place by the application of solder along the edge of the outer member at which it engages the flange of the member 6 as is indicated at 14 in Figs. 1, 7 and 8.

10 If a jar to which the attachment is applied has an indentation as mentioned hereinbefore, the outer flange of the female member of the attachment is likewise indented as at 15 in Fig. 4, and when the member is 15 placed on the jar it is positioned so that its indentation registers with that of the neck 3.

After the members have been secured in the manner hereinbefore explained, the two registering notches or indentations are filled 20 with solder as indicated in black at 16 in Figs. 1 and 2.

To more firmly secure the attachment to the jar, a coating of cement or other adhesive may be applied at the inner surface 25 of the female member as shown at 17 in the drawings, so that after the parts are pressed together it will rigidly adhere to the outer edge of the neck of the jar.

In the form shown in Fig. 7, the flanged 30 cover is attached to the female member of the attachment by means of a hinge joint 18, and in the construction illustrated in Fig. 8, the outer flange of the member is provided with a screw bead 21 for the application of 35 a correspondingly beaded cover 20.

In the use of syrup jars of soda fountains, the bases of their pumps are ordinarily loosely supported upon the necks of the same and it will thus be observed that my 40 invention not only provides means for preventing breakage of the necks of the jars by contact with the metallic parts of the pump and adjacent portions of the fountain, but that it will furthermore make it possible to 45 lift the jars by means of the pumps on account of the rigid connection between the covers 10 to which the pumps are secured, and the outer members 5 of the attachments.

Having thus described my invention what 50 I claim and desire to secure by Letters-Patent is:

1. An attachment of the character described comprising a member having an annular recess adapted to receive the neck of a 55 jar, and a member having a flange adapted to engage a shoulder within the jar opposite to the edge of the neck of the same, the said members fitting snugly one within the other.

60 2. An attachment of the character described comprising a member having an annular recess adapted to receive the neck of a jar, and a member having a flange adapted to engage a shoulder within the jar oppo-

site to the edge of the neck of the same, the 65 said members being slidably fitted one within the other.

3. An attachment of the character described comprising a member having an annular recess, and a member composed of a 70 ring adapted to engage the inner circular surface of said recess, and having at its lower edge, an outwardly projecting flange.

4. An attachment of the character described comprising a member having an annular recess, and means for the attachment 75 of a cover, and a member composed of a ring adapted to engage the inner circular surface of said recess, and having at its lower edge, an outwardly projecting flange. 80

5. An attachment of the character described comprising a member having an annular recess, a cover movably attached to 85 said member, and a member composed of a ring adapted to engage the inner circular surface of said recess, and having at its lower edge, an outwardly projecting flange.

6. The combination with a jar, of a protective covering composed of two coöperative members which are slidably fitted one 90 within the other, and which engage respectively the edge of the neck of said jar, and a shoulder within the jar opposite to the said edge.

7. The combination with a jar, of a protective covering composed of two coöperative members which are slidably fitted one within the other, and which engage respectively the edge of the neck of said jar, and a shoulder within the jar opposite to the 100 said edge, one of said members having means for the attachment of a cover.

8. The combination with a jar, of a protective covering inclosing the neck of the jar and composed of two coöperative members which are slidably fitted one within the other, and which engage respectively the edge of the neck of said jar, and a shoulder within the jar opposite to the said edge. 105

9. The combination with a jar, of a protective covering composed of two coöperative members which are slidably fitted one within the other, and which engage respectively the edge of the neck of said jar, and a shoulder within the jar opposite to the said edge, the said covering and the said jar having registering openings to receive a plastic material for holding the one in its position with relation to the other. 115

10. An attachment of the character described comprising a member having an annular recess, and a member composed of a ring adapted to engage the inner circular surface of said recess, and having at its lower edge, an outwardly projecting flange 120 having a portion of reduced diameter. 125

11. An attachment of the character described comprising two annular members

fitted slidingly one within the other and provided at their outer edges with laterally projecting flanges to respectively engage an interior shoulder of a jar to which the attachment is applied and the edge of the neck of the jar to which said shoulder is opposite.

In testimony whereof I have affixed my signature in presence of two witnesses.

JOHN J. WOMPEY.
